UNITED STATES PATENT OFFICE.

CHARLES H. LITTLE, OF CLEVELAND, OHIO.

DRAFTING INSTRUMENT.

1,003,764.

Specification of Letters Patent. Patented Sept. 19, 1911.

Application filed September 11, 1901. Serial No. 75,004.

To all whom it may concern:

Be it known that I, CHARLES H. LITTLE, a citizen of the United States, resident of Cleveland, county of Cuyahoga, and State 5 of Ohio, have invented a new and useful Improvement in Drafting Instruments, of which the following is a specification, the principle of the invention being herein explained and the best mode in which I have 10 contemplated applying that principle, so as to distinguish it from other inventions.

My invention relates to drafting instruments for drawing parallel lines and particularly to that class of such instruments 15 which combine functions of the parallel ruler and the protractor.

Said invention consists of means herein-after fully described and particularly set forth in the claims.

20 The annexed drawings and the following description set forth in detail certain mechanism embodying the invention, such disclosed means constituting but one of the various mechanical forms in which the principle 25 of the invention may be used.

In its broadest aspects the invention comprises means for carrying a drafting instrument, such as a protractor or ruler, in such manner that it may be moved over the entire area of the drafting board while its angular position is not changed, thereby dispensing with a number of separate drawing tools, each one of which must be separately moved and positioned in order to insure 35 parallelism in executing the work.

In said annexed drawings:—Figure I represents a perspective view of a device embodying my invention secured to a drawing board. Fig. II represents a plan view of 40 same upon an enlarged scale. Fig. III represents a vertical axial cross-section upon an enlarged scale of a form of protractor and its attached parts forming a part of my invention. Fig. IV represents a detail plan view of a portion of the protractor device. Fig. V represents a view taken upon the plane indicated by the line 5—5 in Fig. III, showing the straight-edges or scales used in my invention removed therefrom. Fig. 45 VI represents a vertical longitudinal section of a portion of the protractor device and an attached straight-edge or scale, illustrating a manner of removably securing such straight-edges or scales. Fig. VII represents a vertical transverse section of a 50

form of anchor-support which may be used. Fig. VIII represents a vertical transverse sectional view of a second form of such support.

An anchor support A, Figs. I and II, is 60 secured to one of the upper corners of a drawing board B, the instrument as illustrated being adapted to be secured to the upper left hand corner of such board. Such support consists of a fixable member A² 65 and a pivoted member A', the pivotal bolt a being substantially parallel with the drawing surface, as illustrated. Threaded into the free end of such pivoted member is a screw a² whose lower end bears upon the 70 fixable member A² whereby it is seen the distance of such pivoted member from said fixed member may be variably fixed by turning such screw. Upon said pivoted member A' are pivotally mounted two parallel arms 75 C C of a parallel ruler member, such ruler member being constructed upon the principles of an ordinary parallel ruler, and having for one of its elements the pivoted member of the anchor-support, so that, it is seen, 80 such ruler member is capable of oscillation upon said support. The transverse member C' connecting the free ends of the arms C C of the said ruler member, is provided with pivotal bearings d d upon which are 85 respectively mounted two parallel arms D D of a second parallel ruler member. It is hence seen that said second transverse member C' constitutes an element common to the two parallel ruler members, and that the 90 pivotal bearings are located so that the plane passing through their geometrical axes will intersect the plane passing through the geometrical axes of oscillation of the members or arms C C. It is therefore seen that the oscillation of the compound parallel ruler above described will impart to the transverse member D', connecting the free ends of the arms D D, a "parallel motion", that is a motion such 95 that all points in said connecting member will be simultaneously moved equal distances in like or parallel directions.

It is seen from the above description that the pivoted member A' is capable of movement in a direction transverse relatively to the plane of movement of the parallel ruler members and that the above mentioned screw a² permits same to be variably fixed 105 in such direction.

Upon the connecting member D' is secured the plate E, Fig. IV, upon which is pivotally mounted a circular disk F provided upon its edge with a scaled arc, operating in connection with the fixed line e on said plate, Fig. V, and determining the angular relationship of such disk and the line e, or the connecting member D'. Said disk is provided with a hollow arbor f secured thereto and secured to said arbor is a knob G. The pin f' screwed to the plate E forms the pivotal bearing for the disk and arbor, the upper end of such pin being threaded to receive two lock nuts f², by means of which relative angular movement of the plate and disk may be permitted or said two members be fixed relatively to each other by frictional contact. Secured to the bottom of the disk F is an arm F' to which is removably secured a straight-edge or ruler F². One convenient method of securing such removability is that illustrated in Fig. VI in which the ruler is provided with two metal bushings f³ and the arm F' is provided with two split pins f⁴ which snap into such bushings and so secure the ruler. The split pins f⁴ are secured to the member F' by being forced into suitable apertures therein. In a slot g formed in the knob G and secured to the disk F is a spring stop F³ provided with a stop-pin f⁵ which passes through an aperture formed in said disk and snugly fits into a recess or hole e' formed in the plate E, thereby positively connecting the disk and plate and preventing their relative angular movement. Said hole e' is located so that when engaged by the pin f⁵, the ruling edge of the straight-edge or ruler F² will be located at right angles to the connecting member D'. Arranged with their centers upon the arc of a circle whose center lies upon the geometrical axis of rotation of the disk is a series of holes e² similar to e' and hence adapted to be engaged by the stop-pin f⁵. These holes e² are located so that the disk and plate may be secured to each other as above described, in positions such that the ruling-edge may be caused to occupy the specific angular positions, relative to its above mentioned perpendicular position, of 30, 45, 60, and 90 degrees.

In order to secure the disk and plate at intermediate positions, a clamp G' consisting of a pin threaded into the disk, and bearing upon the plate, as shown in Fig. III, may be used as means auxiliary to the clamp nuts f². Upon the lower surface of said disk F is secured the second arm F⁴ provided with a curved portion f⁶, shown in dotted lines in Fig. V. Said arm is secured by means of two thumb screws f⁷ f⁸, threaded in to the portion f⁶, and passing through the disk, screw f⁸ passing through an elongated slot f⁹ formed in said disk. A second straight-edge or ruler F⁵ is secured to the

arm F⁴ in a manner similar to that in which ruler F² is secured and in a manner such that the ruling edge will be substantially at right angles with the ruling edge of the ruler F². By loosening the thumb screws f⁷ f⁸, thumb screw f⁷ forms a pivotal bearing for arm F⁴ and screw f⁸ oscillates in the slot f⁹. The two rulers may hence be adjusted so as to secure an angle of exactly 90 degrees between the two straight or ruling edges to form a draftsman's square, at the same time permitting the arm F⁴ and ruler F⁵ attached thereto to be entirely and readily removed from the instrument when so desired. Said arms F' and F⁴ are made of metal comparatively thin so as to be more or less flexibly elastic for a purpose hereinafter described.

The above described construction permits the rulers to be moved into any particularly required position upon the drafting board to which the device is attached, one such varied position being illustrated in dotted lines in Fig. II, the successive positions of the straight-edges being parallel with each other. In this manner the straight-edges may be used in lieu of the T-square ordinarily used, and by lifting the spring-stop so as to disengage the plate E and then turning the disk by means of the knob so as to cause the stop-pin to reengage the proper hole e², the straight-edges may be placed at angles of 30, 45, 60, and 90 degrees as may be required, thereby performing the function of the ordinary triangles used by draftsmen. In addition to the above functions one of the straight-edges together with the scaled arc, as is readily understood, may be used as a protractor for measuring angles.

The scales or straight-edges are made readily detachable in order that they may be easily removed and replaced by scales or straight-edges of different character or lengths, such changeability being desirable as will be readily understood.

The arms C C are made of flexible material such as steel of comparatively small thickness, the flexibility being in a direction transverse relatively to the plane of movement of the parallel ruler member. Such flexibility serves two purposes, first, it reduces the possibility of breaking or straining the pivots upon the anchor support, when the device is accidentally struck, and secondly, it permits the scales to lie firm and flat upon the drawing surface. By turning the screw a² the outer end of the parallel ruler member pivoted thereto may be elevated and that part of the parallel ruler members intermediate of the ends caused to travel above and clear the drawing surface, thus allowing the instrument to move freely. In order to secure such above described adjustment, the anchor support is constructed so as to cause the pivoted member thereof to be located a dis-

tance from the drawing surface such that the weight of the parallel ruler members will cause or tend to cause the outer or free ends of the scales to tip upwardly, when 5 the pivoted and fixed members of the support are in contact with each other, and the protractor portion is lying upon the drawing surface, so that it is seen the elevation of such pivoted member to the proper point 10 by means of the adjusting screw will cause the rulers to lie flat as is required. Such result might be obtained by considerable increase of weight of the parts attached to the free end of the parallel ruler device but 15 such increase is objectionable, as will be readily understood, as tending to obstruct the ready manipulation of the instrument. When securing such adjustment, the pivoted support member is elevated as described 20 until the extremity of the second parallel ruler member and its immediately attached parts are caused to be slightly raised from the drawing surface and the free end of the instrument is supported upon the end of the 25 scale or scales attached thereto. The ordinary pressure of the hand upon the knob, will then cause the scales to descend and lie flat upon such surface, the elasticity of the arms F^1 and F^4 permitting such action. 30 As illustrated in Figs. I and II, the fixed member of the anchor support is screwed or otherwise permanently fastened to the drawing board or surface. When however, it is desired to provide an instrument which 35 may be readily detached from the drawing board or surface an anchor support of the form illustrated in Fig. VIII may be provided. In such support the lower fixable member is provided with three or more 40 downwardly projecting sharp pointed lugs, and the upper pivotal member to which the parallel ruler arms are pivoted is made of sufficient weight to properly balance the instrument when the support is placed upon 45 the drawing board or surface without other means for securing same than that offered by the pointed lugs before mentioned. It is preferable to place most of such required balancing weight of metal in such upper 50 member in order to permit the pivoted member to lie with sufficient closeness to permit the pivotal arms of the parallel ruler member to be secured at a distance from the drawing board such that the adjustment 55 of the instrument to cause the rulers or scales to lie flat will be required to be made by elevating the pivoted member, as will be understood from the foregoing description. 60 Other modes of applying the principle 65 of my invention may be employed instead of the one explained, change being made as regards the mechanism herein disclosed provided the means stated by any one of the following claims or the equivalent of such stated means be employed.

I therefore particularly point out and distinctly claim as my invention:—

1. In a drafting instrument, the combination of two members angularly movable relatively to each other, two straight edges 70 secured to one of such members, and means for adjustably securing such straight edges in a right angle relation.

2. In a drafting instrument, the combination of two members angularly movable 75 relatively to each other, two straight edges secured to one of such members at right angles and angularly adjustable relatively to each other, one of such members being provided with means for determining its angular relationship with the other.

3. In combination, an anchor plate, a fixable base to which the anchor plate is pivoted, a pair of parallel ruler members pivoted to the anchor plate to swing transversely to the plane of movement thereof, a cross-bar to which the outer ends of said parallel ruler members are pivoted, and a second pair of parallel ruler members pivoted to the cross-bar, the line of its pivots 85 being transverse to the line of the pivots securing the first-named ruler members to the cross-bar.

4. The combination of an anchor-support having a pivotal member, a parallel-ruler member pivoted to such pivoted support-member, the axes of movement of said pivoted and ruler members being transversely located relatively to each other, means for variably fixing the position of said pivoted 95 member, a second parallel ruler member pivoted to the free end of the first mentioned parallel ruler member, and a straight edge secured to the free end of the second parallel ruler member. 105

5. The combination of an anchor-support, comprising a fixable and pivoted member, a parallel ruler member pivoted to said pivoted member, means for adjustably fixing the pivoted member, a second parallel ruler member pivoted to the free end of the first mentioned parallel ruler member, and a straight edge secured to the free end of the second parallel ruler member. 110

6. In a drafting instrument, a flexible 115 oscillatory parallel ruler device, the flexibility being in a direction transverse relatively to the plane of movement of said device, the arms of the ruler being rigid transversely to that direction.

7. In a drafting instrument, the combination of an anchor-support having a pivoted member, a parallel-ruler device comprising two members, one of the latter being mounted so as to be oscillatory upon such pivoted member, and the other being mounted so as to be oscillatory upon the first, the axes of oscillation of such two ruler members being located in intersecting planes, means for variably fixing the position of said pivoted 125 member, a second parallel ruler member pivoted to the free end of the first mentioned parallel ruler member, and a straight edge secured to the free end of the second parallel ruler member. 130

member, and a straight edge attached to the free end of the outer member of the parallel ruler device.

8. In a drafting instrument, the combination with an oscillating parallel ruler device, of a scale or ruler secured thereto by means of an elastic connection.

9. In a drafting instrument, the combination with an oscillatory parallel ruler device 10 provided at its extremity with a flexible arm, of a scale or ruler secured to said arm.

10. In a drafting instrument, the combination of an oscillatory parallel ruler device, means for adjusting such device in a direction 15 transverse relatively to its plane of movement, and a scale or ruler secured to the free end of said device by means of a flexible connection.

11. In a drafting instrument, the combination 20 of an oscillating parallel ruler device having a plurality of arms, a scale or ruler secured to the free end thereof, the arms of said device being flexible in a direction transverse to the plane of its movement and 25 rigid in the direction parallel with such plane, and means for adjusting said device in a direction transverse to its movement.

12. In a drafting instrument, the combination 30 of an anchor support having a pivoted member, a parallel ruler device comprising two members, one of the latter being mounted so as to be oscillatory upon such pivoted member, and the other being so mounted as to be oscillatory upon the first 35 member, the axes of oscillation of such two ruler members being located in intersecting planes, and means for variably fixing the position of said pivoted member, such parallel ruler device being elastically flexible 40 transversely to the direction of its oscillation.

13. In a drafting instrument, in combination, an anchor block having a fixed member 45 and a member pivoted thereto and oscillating in vertical plane, an adjusting screw passing through the oscillating member and bearing upon the stationary member; and a jointed arm pivoted to the oscillating member and swinging transversely to the direction 50 of oscillation of the latter.

14. In a drafting instrument, in combination, an anchor block having a fixed member and a member pivoted thereto and oscillating in vertical plane, an adjusting screw 55 passing through the oscillating member and bearing upon the stationary member; and a jointed arm pivoted to the oscillating member and swinging transversely to the direction of oscillation of the latter, such arm being elastically flexible in a direction transverse to the direction of its oscillation.

15. In a drafting instrument, in combination, an anchor block having a fixed member and a member pivoted thereto and oscillating in vertical plane, an adjusting screw

passing through the oscillating member and bearing upon the fixed member, a pair of parallel bars pivoted to the oscillating member, a cross-bar pivotally uniting the outer ends of the bars, a second pair of arms pivotally attached to the cross-bar, lines passing respectively through such two sets of pivots in the cross-bar intersecting, and a head pivotally uniting the outer ends of said second named pair of arms.

16. In combination, a drafting board, a pivoted anchor block attached at one corner of the board, a parallel ruler member pivoted to the block, a second parallel ruler pivoted to the outer end of the first-mentioned ruler member, and a drawing implement attached to the outer end of the second named ruler member, the two sets of parallel ruler members swinging on their pivots in planes transverse to the plane of oscillation of the anchor block.

17. In combination, a drafting board, a pivoted anchor block attached at one corner of the board, a parallel ruler member pivoted to the block, a second parallel ruler pivoted to the outer end of the first-mentioned ruler member, the lines passing through the pivots of each ruler member at the connected ends of such members intersecting, and a drawing implement attached to the outer end of the second named ruler member, the two sets of parallel ruler members swinging on their pivots in planes transverse to the plane of oscillation of the anchor block.

18. In combination, a drafting board, an anchor block attached at one corner of the board and having an oscillating member, a stop for limiting the approach of the oscillating member of the block toward the board, a parallel ruler member pivoted to the block, a second parallel ruler member pivoted to the outer end of the first-mentioned ruler member, the side arms of the parallel rulers being flexible in a direction 105 transverse to the direction of their oscillation, and a drawing implement attached to the outer end of the second named ruler member.

19. In a drafting board, in combination, an anchor block secured thereto, a jointed arm pivotally attached to the block and swinging over the board and supported by the block out of contact therewith, such arm being formed of bars flexible in a direction 110 transverse to its oscillation and rigid in the plane of oscillation, and a drafting implement carried by the jointed arm.

20. In combination, an anchor support; a parallel ruler pivotally attached to the anchor support; a second parallel ruler pivotally attached to the outer end of the first parallel ruler, the pivots at the adjacent ends of the two parallel rulers being in intersecting planes; a protractor attached to 130

- the outer end of the second parallel ruler; and a straight edge attached to the protractor.
21. In a drafting instrument, an oscillatory parallel ruler device having flexible arms, the flexibility being greater in a direction transverse to the plane of movement of the device than in said plane, and means for adjusting the parallel ruler device in planes transverse to the direction of its oscillation.
22. In a drafting machine, in combination, a parallel ruler member comprising arms flexible in a direction transverse to the plane of its movement, and an anchor for such member upon which it oscillates and adapted to hold it away from the surface with which it may be used and means for adjusting the parallel ruler device in planes transverse to the direction of its oscillation.
23. In a drafting machine, in combination, a parallel ruler member, an anchor therefor adapted to hold such member away from the surface with which it is to coöperate, and a second parallel ruler member mounted at the free end of the first-mentioned ruler member, one of such ruler members comprising arms flexible in a direction transverse to the plane of its oscillation and means for adjusting the parallel ruler device in planes transverse to the direction of its oscillation.

24. In a drafting machine, in combination, two parallel ruler members, one being carried by a fixed anchor and carrying the other, one of such ruler members comprising arms flexible in a direction transverse to the plane of their movement and means for adjusting the two parallel ruler members to different planes of movement.

25. In combination, a drafting board, a jointed arm pivotally attached to the board, a protractor mounted upon the outer end of the arm, and a square attached at its angle to the protractor.

26. In combination with a drafting board, a head graduated in degrees, a support, clamps secured to the head, scaled rules removably secured to the clamps, means connected with the head and support for carrying the rules consisting of a jointed arm formed in sections and pivoted on common centers and one end of the jointed arm pivoted to the support, and the other end pivoted in the head, and means connected with the head for changing the angles of the rules.

Signed by me, this 7th day of September, 1901.
